UNITED STATES PATENT OFFICE

165,373

HOOD

Virginia C. Hayes, Chicago, Ill.

Application March 7, 1951, Serial No. 14,407

Term of patent 14 years

(Cl. D3—13)

To all whom it may concern:

Be it known that I, Virginia C. Hayes, a citizen of the United States, residing at Chicago, in the county of Cook and State of Illinois, have invented a new, original, and ornamental Design for a Hood, of which the following is a specification, reference being made to the accompanying drawing, forming a part hereof.

In the drawing:

Fig. 1 is a side elevational view of a hood embodying my new design;

Fig. 2 is a front elevational view thereof; and

Fig. 3 is a rear elevational view of the same.

I claim:

The ornamental design for a hood, substantially as shown.

VIRGINIA C. HAYES.
